PULLING-OVER MACHINE

Bernhardt Jorgensen, Beverly, Mass., assignor to
 United Shoe Machinery Corporation, Paterson,
 N. J., a corporation of New Jersey

Application December 21, 1933, Serial No. 703,444

9 Claims. (Cl. 12—4)

This invention relates to upper-pulling or pulling-over machines and more particularly to improved mechanism for controlling the relative movement of the upper-gripping means and the last or form in the upper-pulling operation. Although the invention is herein illustrated in its application to the control of the side grippers in a machine of the type commonly used for pulling over uppers, the invention is not limited to side gripper control nor to an organization of the particular type illustrated.

Various expedients have been adopted or proposed heretofore for controlling the upper-pulling movements of the upper-engaging grippers in pulling-over machines. It is well known, for example, to employ a fluid check for retarding the movements of the grippers and thus insuring that they shall exert a slow steady pull upon the upper such as will have no tendency to tear or injure it. It has been proposed to provide for automatically relieving the resistance of the fluid check at a predetermined time in the cycle of operations of the machine to insure that the grippers when released from the upper shall be quickly retracted into positions out of the way of the overlaying and tacking devices. It is also well known to provide mechanism including a hand lever for supplementing the action of the updraw springs so as to increase at will the pull of the grippers upon the upper.

In order to provide for still better control of the relative movement of the upper-gripping means and the last or form in an upper-pulling machine there is provided, in accordance with the present invention, a novel organization of controlling mechanism which, as herein illustrated, comprises a hand lever that is operable at will to cause the side grippers to exert upon the upper a stronger pull than that derived from the updraw springs, and a fluid check which is normally effective to retard the upper-pulling movement but which is so constructed and arranged and so connected with the hand lever that, upon actuation of the latter to increase the pull on the upper, the retarding action of the fluid check will be automatically relieved. In the organization herein shown the hand lever is movable in one direction to retard the upper-pulling movement to a greater extent than it is normally retarded by the action of the fluid check and in the opposite direction to increase the pull exerted upon the upper, and the fluid check comprises a fluid-containing cylinder having a piston movable therein in response to the upper-pulling movement of the side grippers and a valve normally held by a

spring in position to restrict and regulate the flow of the fluid through an opening in the cylinder. As illustrated also, the tension of the valve spring and the construction and arrangement of the operative connections between the piston and the hand lever are such that when the hand lever is moved in a direction to increase the pull on the upper, so that the grippers are operated with greater force than that normally applied through the updraw springs, the pressure exerted by the piston on the fluid in the cylinder will be increased sufficiently to cause the valve to open wider and thus to relieve the resistance to the flow of the fluid through the cylinder opening to such an extent that the fluid check will offer little if any substantial resistance to the movement of the hand lever and a very sensitive and efficient manual control of the upper-pulling movement is afforded.

Further in accordance with the present invention the means for retarding the relative movement of the upper-engaging grippers and the last in the upper-pulling operation comprises novel and improved mechanism for automatically relieving the resistance of the retarding means at a predetermined time in the cycle of operations of the machine to insure a quick withdrawal of the grippers into out-of-the-way positions when they are released from the upper. This improved mechanism, as herein illustrated, comprises a cam on the rockshaft which is operated to swing the tacking devices inwardly into positions for the driving of the tacks, and operative connections between this cam and the valve which regulates the retarding action of the fluid check, these operative connections being constructed and arranged to open the valve wider to relieve the retarding action of the fluid check and thereafter to permit the valve spring to return the valve to its normal position. As illustrated, also, the valve-operating cam may be so constructed and so mounted that it may be quickly and conveniently adjusted upon its shaft to vary the time when the automatic operation of the valve takes place.

Invention further resides in various novel combinations and arrangements of parts including certain particulars of construction of the fluid check and associated controlling mechanism all of which will now be described with reference to the accompanying drawings and pointed out in the claims.

In the drawings,

portion of a pulling-over machine embodying the novel features of the invention;

Fig. 2 is a view, partially in side elevation and partially in section and on an enlarged scale, 5 of the mechanism for retarding the updraw movements of the side grippers;

Fig. 3 is a detailed view in side elevation of the cam mechanism for automatically relieving the resistance of the retarding mechanism;

10 Fig. 4 is a top plan view, partially broken away, of the mechanism shown in Fig. 3;

Fig. 5 is a side elevational view of a cam of modified form which may be employed to effect the automatic opening of the valve for relieving 15 the action of the fluid check; and

Fig. 6 is a plan view, partially broken away, of the modified cam and associated parts showing how the cam may be mounted to facilitate manual adjustment of the cam upon its shaft.

20 Referring to the drawings, the invention is therein shown as embodied in a pulling-over machine of a well-known commercial type having a sole rest 10, a heel rest 12, and side clamps, one of which is shown at 14. In common with other machines of this type, the illustrated machine is provided also with two sets of side grippers, one set of which is indicated by dotted lines at 16, and with the usual side wipers and associated tacking devices, one of the side wipers 30 being indicated at 18 and the tacking device associated therewith at 20. As indicated the illustrated tacking devices include tack driver bars 22 which are raised against spring tension by mechanism that swings about a cam-operated 35 rockshaft 24 and are subsequently depressed by spring action to drive tacks for fastening the upper to the insole and last when they are released by portions of that mechanism operated by turning of the rockshaft 24. Such turning of the 40 rockshaft further serves to swing the tacking devices and the wipers 18 thereon inwardly over the shoe bottom just before the driver bars are released. The illustrated side grippers 16 comprise gripper jaws which are carried by gripper casings 25, the latter being connected by means of operating bars 26 with updraw levers 27. As shown, the updraw levers 27 are mounted upon a pivot rod 28 and are connected at their rear ends to a cam-operated slide 30 through updraw 45 springs 32 mounted upon rods 34 on the slide 30, the springs being arranged to be compressed by the downward movement of the slide to operate the grippers 16 yieldingly. As in other machines of this type, also, the updraw levers 27 of the 50 illustrated machine are connected to an equalizing lever 36 which is mounted for turning movement in a block 38 about an axis extending lengthwise of the updraw levers, the block 38 being fast upon a rockshaft 40 which carries a 55 gear segment 42 operatively engaged with a co-acting gear segment 44 on a hand lever 46 which is pivoted upon the rod 28 and is arranged to permit manual control of the movements of the side grippers when desired. The equalizing lever 60 65 65 bears upon the upper edges of the updraw levers 27 and is connected to these levers by means of cradle members 48 so that the swinging movements of the levers in either direction are accompanied by a swinging movement of the equalizing lever 36 about the axis of the rockshaft 40, the lever 36 being permitted to turn in the block 38 to accommodate itself to different relative positions of the updraw levers. 70 The construction and mode of operation of all 75 of the operative parts above referred to, with the

exception of the side wipers 18, the hand lever 46, and the equalizing mechanism for the updraw levers, are substantially the same as of corresponding parts of the pulling-over machine disclosed, for example, in United States Letters Patent No. 1,029,387, granted June 11, 1912, upon application of R. F. McFeely. The side wipers are substantially the same in construction and mode of operation as corresponding parts in the machine disclosed in United States Letters Patent 10 No. 1,409,190, granted March 14, 1922, upon application of R. F. McFeely, while the construction and mode of operation of the equalizing mechanism and the construction and arrangement of the hand lever 46 are substantially the same as 15 of corresponding parts disclosed in United States Letters Patent No. 1,448,742, granted March 20, 1923, upon application of Joseph Gouldbourn. Reference may be had to the above-mentioned 20 patents for details of construction and operation of the illustrated machine not herein fully disclosed.

25 In the operation of the illustrated machine it will be understood that the sole rest 10 engages the insole to prevent the last from moving upwardly and is operated to sink the last downwardly into the upper during the upper-pulling movements of the grippers and that the heel rest 12 is moved into engagement with the heel end of the last to resist the backward strains to which 30 the last is subjected in the upper-pulling operation. It will also be understood that upon the starting of a cycle of operations of the machine the slide 30 receives a comparatively quick downward movement from its operating cam and that, 35 through the springs 32, the updraw levers 27 are thereby operated to close the gripper jaws upon the upper and then to pull the upper over the last until the resistance of the tensioned upper balances the force of the springs which react to 40 complete the pulling of the upper after the slide 30 has completed its downward movement. The machine comes automatically to a stop with the upper under tension and upon a subsequent actuation of the starting means the side clamps 14 45 are swung inwardly at opposite sides of the shoe to clamp the tensioned upper to the last. Thereafter the side wipers 18 are operated to wipe the margin of the upper inwardly over the edges of the insole on the last by inward swinging movements of the tacking devices 20 which carry them, and immediately thereafter the driver bars 22 are released to drive the tacks and thereby to fasten the over-wiped upper margins to the insole and the last. The inward movements of the 50 tacking devices and the release of the driver bars result from the turning of the rockshaft 24, as hereinbefore explained. In the course of the inward movements of the side wipers 18 and the tacking devices 20 the side grippers 16 are tripped 55 to cause them to release the upper, whereupon the grippers are quickly withdrawn to positions out of the way of the tacking devices by means of overdraw springs (not shown) which act to swing them inwardly as they are moved farther 60 upwardly by the updraw levers 27 under the influence of the springs 32. Subsequently the updraw levers are positively returned to starting positions by upward movement of the cam slide 30 and the grippers are swung outwardly into 65 70 75 positions to receive the next upper.

For the purpose of retarding the upper-pulling movements of the side grippers 16 the illustrated machine is provided with a liquid check comprising a liquid-containing cylinder 50 (Fig. 2) having 75

a hollow piston 52 therein which is caused to move downwardly in response to upward movements of the updraw levers 21. The cylinder 50 is formed within a casing 54 which is rigidly secured by means of screws 56 to the frame of the machine and within which is formed a liquid chamber 58 which is arranged to communicate with the lower portion of the cylinder 50 through a passage 60 controlled by the cooperation of a valve 62 with a valve seat 64 at one end of the passage 60. Provision is also made for communication between the cylinder 50 and the chamber 58 through a central passage 66 in the head of the hollow piston 52 and branch passages, one of which is shown at 68, radiating from the central passage 66, the flow of liquid through these passages being controlled by means of a valve 70 arranged to cooperate with a valve seat 72 formed at the lower end of the passage 66. The chamber 58 and the cylinder 50 are adapted to be filled with liquid, for example oil, through an opening 74 in a cover 75 which is secured by means of screws 76 to the top of the casing 54, the opening 74 being normally closed by means 25 of a screw plug 78. The piston 52 is urged upwardly in the cylinder 50 by means of a coiled spring 80 the lower end of which is seated upon the bottom of the cylinder and the upper end of which extends into the hollow piston and bears upon a washer 82 which is held by the spring 80 against the piston head. The force of the spring 80 holds the piston head against the rounded free extremity of a curved arm 84 which is rigidly secured to a rockshaft 86 that is journaled in bearings in the casing 54. Upon actuation of the rockshaft 86 the curved arm 84 functions to move the piston 52 downwardly within the cylinder 50. As shown, a disk-shaped wear plate 88 is countersunk within the head of the piston to provide a suitable bearing for the end of the curved arm 84. The rockshaft 86 is connected with the updraw levers 21 by means comprising an arm 90 which is rigidly secured to one end of the rockshaft 86, a link 92 connecting the arm 90 with the hand lever 46, and the equalizing mechanism hereinbefore described which connects the hand lever 46 with the updraw levers. Provision is thereby made for moving the piston 52 downwardly in response to upward movement of the updraw levers and the side grippers. During such downward movement of the piston 52 the valve 70 is held against its seat 72 by means of a light spring 94 the upper end of which bears against the valve 70 and the lower end of which is seated upon inwardly turned extremities of fingers 96 which extend downwardly from the washer 82. The tension of the light spring 94 is such that the spring will yield upon upward movement of the piston to open the valve 70 an amount sufficient to permit the liquid to flow freely from the chamber 58 through the passage 66 into the upper end of the cylinder 50 as the updraw levers are returned to their starting positions.

Upon downward movement of the piston 52 responsive to upward movement of the updraw levers derived from the updraw springs 32 the valve 62 functions to restrict the flow of liquid from the cylinder 50 through the passage 60 into the chamber 58 so as to retard the downward movement of the piston and, through the connections between the piston and the updraw levers, to retard the upward pulling movements of the side grippers. Provision is made whereby the valve 62 is opened farther automatically at a predetermined time in the cycle of operations of the machine to relieve the resistance of the fluid check to the upward movements of the grippers and whereby the valve 62 is opened for the same purpose if and when the operator moves the hand lever 46 in a direction to cause the grippers to exert a stronger pull upon the upper. To enable the valve to be operated in this manner it is formed with a stem 100 which extends outwardly through a bushing 102 having at its inner end external screw threads 104 in engagement with threads formed in an opening 106 in the outer wall of the chamber 58. To prevent outward leakage of liquid along the outer side of the bushing 102 the inner side of an external flange 108 on the bushing 102 bears against a gasket 110 that is seated in a counterbore in the opening 106, the bushing being formed with a hexagonal outer portion 112 adapted to be engaged by a wrench for use in tightening the flange 108 against the gasket 110. The valve stem 100 is adapted to slide freely within the bushing 102 and it is normally urged in a direction tending to close the valve 62 by means of a spring 114 which encircles the valve stem, one end of the spring bearing against the valve 62 and the other end of the spring bearing against the inner end of the bushing. The strength and tension of the spring 114 are such that the spring will not yield to permit further opening of the valve 62 under the influence of any pressure developed by downward movement of the piston 52 in response to normal upward movement of the updraw levers under influence of the springs 32, but will yield to permit the valve to open wider 35 so as to offer no substantial obstruction to the flow of the liquid through the passage 60 when the piston 52 is depressed in the operation of the updraw levers by manipulation of the hand lever 46 in a manner hereinafter to be described. In 40 order that the valve 62 shall function to restrict as desired the flow of liquid through the passage 60 it is normally held retracted against the force of the spring 114 in a slightly open position, such as that shown in Fig. 2, by means of a nut 116 45 on the threaded outer portion 118 of the bushing 102 arranged to engage the inner flanged end of a spool or sleeve 120 on the valve stem 100, the spool 120 having internal screw threads in engagement with threads on the outer portion of 50 the valve stem and being adapted to receive between its flanges 122 the lower forked extremity 124 of a cam-actuated lever 126. The lever 126 is pivoted at 128 to an ear 130 on the casing 54 and is operated automatically to open the 55 valve 62 farther after the completion of the upper-pulling operation, as will be hereinafter explained. As shown, the nut 116 is split and provided with a binding screw 132 for clamping it in adjusted position on the bushing 102 and the 60 nut is formed with a wing 134 by means of which it may be manually turned to adjust the valve 62 so as to vary the size of the opening between the valve and its seat 64 when the valve occupies its normal position. As shown, also, the outer flange of the spool 120 is knurled and a screw-driver slot 136 is formed in the outer end of the valve stem to facilitate relative turning of the spool and the valve stem for purposes of setting-up adjustment of the valve mechanism. A check nut 138 on the valve stem 100 is adapted to be tightened against the outer end of the spool 120 to prevent accidental displacement of the spool and the valve stem from their relatively adjusted positions.

During the progress of the upper-pulling operation under power the operator may find that in certain instances it is advantageous to hasten the pulling movement or he may find it desirable in order more effectively to tension the upper, either before or after the grippers have completed their normal pulling movements, to cause them to exert a more powerful pull on the upper than that derived from the updraw springs.

10 The operator may accomplish either of these results by giving a comparatively quick backward push to the hand lever 46. This movement of the hand lever will operate through the connections between the lever and the curved arm 84 to 15 impart a sudden downward movement to the piston 52 which will increase the pressure of the fluid within the cylinder sufficiently to compress the spring 114 and open the valve 62 wider so as to relieve the retarding action of the fluid check. This will cause the updraw springs to 20 raise the grippers more quickly if the stresses of the springs have not already been balanced by the resistance of the upper. By means of the backward push upon the hand lever, moreover, 25 the force exerted by the updraw springs may be supplemented to a substantial extent by manual force to provide any desired amount of operator-controlled additional pulling or stretching of the upper, such stretching being substantially unopposed by the fluid check inasmuch as the valve 30 62 in the latter will be kept open by the fluid pressure within the cylinder 50 resulting from the movement of the hand lever.

The lever 126 is operated automatically to open the valve 62 to relieve the retarding action of the liquid check at a predetermined time in the cycle of operations of the machine by means comprising a cam 140 (Figs. 3 and 4) on the rockshaft 24, a cam roll 142 engaged with the periphery of the cam 140, and a rod 144 which carries the cam roll 142. As shown, one end of the rod 144 is pivoted at 146 to the upper extremity of the lever 126 and the opposite end of the rod is forked at 148 (see Fig. 3) to embrace a boss 150 formed on the outer side of the cam 140 and is held in place by means of a flange 152 on the boss 150. The cam 140 is rigidly secured to the end of the rockshaft 24 by means of a clamp screw 154, the radial position of the cam relatively to the rockshaft being determined by means of a dowel pin 156 which extends from the end of the rockshaft into the cam.

The cam 140, as shown in Fig. 3, is so constructed that it will operate to open the valve 62 as soon as the rockshaft 24 begins to turn in the direction to swing the tacking devices inwardly toward the shoe. If desired, however, a cam of modified construction may be employed such, for example, as the cam 140a shown in Figs. 5 and 6, wherein a substantial dwell 140b is provided in the low part of the cam for the purpose of delaying the opening of the valve 62. In order that the time when the valve is opened may be varied more or less according to the requirements of the particular work being operated upon, provision may be made for adjusting the cam 140a about the axis of the rockshaft 24. To this end, as shown in Fig. 6, the use of a dowel pin for holding the cam in place upon the rockshaft is eliminated and the cam is secured to the end of the rockshaft by means of a clamp screw 154a having a knurled head 154b by means of which the screw may be readily turned for the purpose of clamping or releasing the cam. Upon loosening the clamping screw 154a the cam 140a may be quickly and con-

veniently adjusted to vary the time when it shall be effective to open the valve. As shown, the cam 140a is held positively in adjusted position when the clamp screw 154a is tightened by means of a series of radial teeth 158 on the inner face of the hub of the cam 140a arranged to cooperate with corresponding series of radial teeth 160 formed on the end of the shaft 24. By appropriate adjustment of the cam 140a it is practicable to delay the time when the retarding action of the fluid check is relieved until after the side wipers 18 have engaged the margins of the upper and pressed them against the edges of the insole so that they are adapted to supplement the action of the side clamps in holding and controlling the upper at the time when the grippers are caused to release the upper.

In the use of the machine the valve 62 in the fluid check will be manually adjusted by manipulation of the nut 116 to restrict as desired the flow of liquid through the opening 60 so as to retard the upper-pulling movements of the side grippers to such an extent as may be found necessary or desirable to insure against injury to the shoe upper, having regard to the character of the upper and the strength of the updraw springs. In operation the fluid check is effective to retard the upward movements of the side grippers when the machine is started, and, unless the hand lever 46 is moved manually in a direction to increase the pull of the grippers upon the upper, the fluid check will continue its retarding action until the grippers come to rest or until the valve 62 is opened by means of the automatic mechanism including the lever 126 and the cam 140 on the rockshaft 24. At any time while the upper is being pulled, the operator, by pulling forwardly upon the hand lever 46, may retard the pulling movement even more than it is being retarded by the action of the fluid check and in this way cause the upper to be stretched as slowly as may be desired for best results upon the particular shoe being operated upon. On the other hand, the operator, watching the progress of the pulling operation, may observe that the grippers, rising slowly and steadily under the retarding action of the fluid check, may not be properly tightening the upper over the last, and under such circumstances he may push the lever backwardly to increase the downward pressure upon the piston 52 and thereby to cause the valve 62 to yield so as to relieve more or less the resistance of the fluid check and thus permit the grippers to be raised more rapidly by the force of the updraw springs and thereby to stretch or tighten the upper more effectively. In this way, as already pointed out, the operator may manually supplement the force exerted by the updraw springs to transmit a more powerful pull to the upper in case the condition of the latter is such as to warrant such action. Moreover, after the stresses of the updraw springs have become balanced by the resistance of the upper so that the springs are no longer effective to increase the tension of the upper, the operator, by backward pressure upon the control lever 46, may manually exert such force as may be necessary satisfactorily to complete the upper-pulling operation and he may repeatedly stretch the upper in this way if desired. In all cases the operator may thus cause manual force to be applied to the grippers before the valve 62 has been automatically opened in the second stage of the cycle of operations of the machine. Such force will be substantially unopposed by the fluid check inasmuch as movement of the control lever ma- 75

nipulated as hereinbefore described will be effective to cause wider opening of the valve so as substantially to cut out the resistance normally offered by the fluid check to the pulling of the upper.

Having thus described my invention, what I claim as new and desire to secure by Letters Patent of the United States is:

1. In an upper-pulling machine, in combination, upper-gripping means, means for pulling an upper yieldingly over a last by relative movement of said upper-gripping means and the last, controlling mechanism for said upper-pulling means including a fluid check for retarding said upper-pulling movement, a valve for regulating the action of the fluid check, mechanism arranged to be operated manually to supplement the pulling action of said upper-pulling means, means operable at a predetermined time in the cycle of operations of the machine to open said valve to relieve the resistance of the fluid check, and other means controlling said valve and yieldable to permit said manually-operated mechanism to open the valve through the medium of the fluid in the fluid check and thus to relieve the resistance of the check.

2. In an upper-pulling machine, the combination with upper-gripping means and means for pulling an upper yieldingly over a last by relative movement of said upper-gripping means and the last, of a fluid check for retarding said upper-pulling movement, mechanism including a spring-controlled valve automatically operative at a predetermined time in the cycle of the machine to relieve the resistance of said fluid check to further relative movement of the upper-gripping means and the last in the direction of pull by the opening of the valve against the action of its spring, and manually-operable means for increasing the pressure of the fluid in said fluid check and thereby by opening said valve to lessen the resistance of the fluid check at the will of the operator.

3. In an upper-pulling machine, in combination, upper-gripping means, operating mechanism including an updraw spring for imparting yielding movement to said upper-gripping means to pull an upper, a fluid check for retarding the upper-pulling movement of said gripping means comprising a cylinder having a piston movable therein, operative connections between said piston and said upper-gripping means for moving the piston in response to said upper-pulling movement, and a valve for regulating the flow of fluid in said check to control said retarding action, said valve being unaffected by pressure of said fluid caused by normal movement of said piston but being operable by increased pressure of said fluid to relieve the retarding action of the fluid check, and said operative connections including a member adapted to be moved manually in one direction to supplement the retarding action of the fluid check and in another direction to supplement the force applied to said piston in the upper-pulling operation and thus to increase the pressure of said fluid and thereby operate the valve to relieve said retarding action.

4. In an upper-pulling machine, upper-gripping means, automatic operating means for yieldingly effecting relative movement of said upper-gripping means and a last to pull an upper over the last, a member movable by the operator for also effecting such relative movement to increase the force of the pull on the upper, a fluid-containing device for retarding said relative movement by resistance to flow of the fluid in said device, a

valve controlling the flow of the fluid and so arranged that pressure of the fluid thereon tends to open it, a spring acting on said valve in opposition to the pressure of the fluid thereon, means cooperating with said spring to hold the valve normally in a position affording a restricted opening for flow of the fluid, said spring being yieldable to permit a wider opening of the valve in response to such pressure of the fluid on the valve as results from movement of said member by the operator, and mechanism for also opening the valve independently of the pressure of the fluid thereon.

5. In an upper-pulling machine, upper-pulling grippers and automatic mechanism for operating them to pull an upper over a last, said grippers being releasable from the upper and adapted to be withdrawn to out-of-the-way positions, a member movable by the operator for also operating said grippers to increase the force of the pull on the upper, a fluid-containing device for retarding the movements of said grippers by resistance to flow of the fluid in said device, a valve controlling the flow of the fluid and so arranged that pressure of the fluid thereon tends to open the valve, a spring acting on said valve in opposition to the pressure of the fluid thereon, means cooperating with said spring to hold the valve normally in a position affording a restricted opening for flow of the fluid, and automatic means for opening said valve wider to relieve the resistance to the flow of the fluid and thereby to facilitate the withdrawal of said grippers, said spring being yieldable to permit a wider opening of the valve only in response to the operation of said automatic means and to such pressure of the fluid on the valve as results from movement of said member by the operator.

6. In an upper-pulling machine, in combination, upper-pulling grippers and means for operating them to pull an upper over a last, said grippers being releasable from the upper and adapted to be withdrawn to out-of-the-way positions, means for retarding the upper-pulling movements of said grippers, tacking devices for securing the pulled-over upper to the last, mechanism including a rockshaft for moving said tacking devices into operative positions, and means including a cam on said rockshaft for lessening the resistance of said retarding means to movement of the grippers and thereby facilitating withdrawal of said grippers after they have released the upper.

7. In an upper-pulling machine, in combination, upper-pulling grippers and means for operating them to pull an upper over a last, said grippers being releasable from the upper and adapted to be withdrawn to out-of-the-way positions, a fluid check for retarding the upper-pulling movements of said grippers, a valve normally held by a spring in position to control the retarding action of said fluid check, normally retracted tacking devices for securing the pulled-over upper to the last, mechanism including a rockshaft for moving said tacking devices into operative positions, and mechanism including a cam on said rockshaft for opening said valve against the tension of said spring to relieve the retarding action of said fluid check and thus to facilitate the withdrawal of said grippers.

8. In an upper-pulling machine, in combination, upper-pulling grippers and means for operating them to pull an upper over a last, said grippers being releasable from the upper and adapted to be withdrawn to out-of-the-way po-

- 5 sitions, means for retarding the upper-pulling movements of said grippers, tacking devices for securing the pulled-over upper to the last, mechanism including a rockshaft for moving said 10 tacking devices into operative positions, and means including a cam on said rockshaft for lessening the resistance of said retarding means to movement of the grippers and thereby facilitating the withdrawal of said grippers, the construction and mounting of said cam being such as to permit adjustment of the cam to vary the time when the resistance of the retarding means is lessened.
- 15 9. In an upper-pulling machine, in combination, upper-pulling grippers and means for operating them to pull an upper over a last, said grippers being releasable from the upper and adapted to be withdrawn to out-of-the-way positions, a

fluid check for retarding the upper-pulling movements of said grippers, a valve for regulating the action of the fluid check, normally retracted wipers movable inwardly into positions for engaging the margin of the upper and wiping it inwardly over the insole, normally retracted tacking devices for securing the overwiper upper margin to the last, mechanism including a rockshaft for moving said tacking devices into operative positions, and means including a cam on said rockshaft for opening said valve to lessen the resistance of said retarding means to movement of the grippers and thereby to facilitate the withdrawal of the grippers, said cam being constructed and arranged to delay the opening of said valve until the wipers have engaged the upper.
